UNITED STATES PATENT OFFICE.

HERMAN W. VITT, OF UNION, MISSOURI.

MILLSTONE DRIVER AND RYND.

SPECIFICATION forming part of Letters Patent No. 241,456, dated May 10, 1881.

Application filed January 4, 1881. (No model.)

To all whom it may concern:

Be it known that I, HERMAN W. VITT, of Union, in the county of Franklin and State of Missouri, have invented a certain new and useful Improvement in Millstone Drivers and Rynds, of which the following is a full, clear, and exact description, reference being had to the accompanying drawings, forming part of this specification.

10 My improvement relates to a device for communicating motion from the spindle to the stone, the construction being such as to allow the runner to run true, though the spindle may be out of tram or sprung.

15 Millstones as usually driven admit of no accurate running-balance, owing to the construction of the driving device. The ordinary driving device consists of rigid arms or driver extending from the spindle and engaging the stone at points below the point of balance at the cock-head. The consequence is that if either the driver or its bearings upon the stone are not true, or the spindle is not in tram, or sprung, that the runner cannot run true, for 25 reasons which will be obvious.

20 In the drawings, Figure 1 shows the improvement chiefly in axial section, with the stones mostly in elevation. Fig. 2 shows the eye-lining, in section at $x^2 x^2$, Fig. 4, with the other 30 parts in elevation. Fig. 3 is a section at $x^2 x^2$. Fig. 4 is a top view of the improvement. Fig. 5 is a horizontal section at $x x$, Fig. 3. Fig. 6 is a horizontal section at $x' x'$, Fig. 3.

25 I have shown my improvement as applied to an upper runner. It may, of course, be applied equally well to a lower runner.

30 A is the bed-stone. B is the runner. C is the eye of the runner and D is the metal lining of the same, with an inturned circular 40 flange, d, which gives means for the attachment of the circular balance piece or rynd E cast in one piece and composed of a flange, e, at top, extending beneath and bolted to the flange d, as shown at F, and a flat circular part, e³, connected to the flange by bars e', between 45 which are side openings, e², for the outward passage of the grain. The rynd E has in the bottom a recess to receive the cockeye-block G.

45 e⁴ are lugs extending downward at opposite 50 sides of the rynd, and having vertical slots e⁵, to receive studs h, projecting from the driver-ring H. The studs h are at opposite sides of

the ring, and at points intermediate between them project similar studs h', which occupy slots i' in the lugs or extensions i at the upper 55 edge of the drive-cylinder I. The drive-cylinder surrounds the spindle K, as shown, and is supported on the ends k' k' of a pivot-pin, k, passing through the spindle, in order to equalize the pressure of the driving-power, said ends 60 k' k' occupying slots or recesses i² at the lower edge of the drive-cylinder. Thus it will be seen that there is the utmost freedom of accommodation between the balance-rynd and the spindle, as the drive-ring and its connections form a universal joint between them. K' is the cock-head at the upper end of the spindle, forming the point of suspension of the runner, and sustaining the whole weight of the same.

70 Now, supposing the spindle should not be exactly vertical or "in tram," it will be seen that my driving device would not interpose any obstacle to prevent the stone running in a horizontal position, because there would be 75 perfect freedom of movement between the cock-eye-piece E and the spindle.

I will call attention to an important point of construction in this connection, viz: The upper end of the cock-head is in the same plane as the 80 axis of the driving-studs h h'. Thus in all the deviations of the stone relatively with the spindle or the springing of the spindle the movement would be made upon the point of the cockhead-bearing, as a center of movement, 85 and there would be no binding of parts, checking the easy and perfect adjustment. It will be seen that the parts would adapt themselves to compensate for the imperfections in their constructions, without tending to throw the 90 stone out of its horizontal position.

95 It will be observed that the rynd E can be readily taken out by unscrewing the bolts F, and again returned to exact position. Thus any necessary repairs may easily be made to this part.

I claim herein as my invention—

1. The combination, with the spindle K, having pin k, and the drive-cylinder I, provided with slots i' i², of the driving-ring H, having 100 studs h h', rynd E, having the flange e, circular part e³, and slotted lugs e⁴, substantially as described, and for the purpose set forth.

2. The rynd E, cast in one piece and com-

posed of the top flange, *e*, flat circular part *e*³, connected to the flange by bars *e'*, between which are side openings, *e*², for the grain, a recess in the bottom to receive the cockeye-block, 5 and lugs *e*⁴, extending downward at opposite sides and having vertical slots *e*⁵, substantially as described.

3. The combination, with the runner *B*, having an eye-lining, *D*, with inturned circular 10 flange *d*, of the rynd *E*, provided with the top

flange, *e*, circular part *e*³, bars *e'*, openings *e*², and slotted lugs *e*⁴, driving-ring *H*, having studs *h* *h'*, drive-cylinder *I*, and spindle *K*, having pin *k*, substantially as described, and for the purpose set forth.

HERMAN W. VITT.
